A. I. Woodring, by
G. E. Kennedy,
Attorney.

UNITED STATES PATENT OFFICE.

ALBERTO I. WOODRING, OF WATERLOO, IOWA, ASSIGNOR TO THE A. I. WOODRING COMPANY, OF WATERLOO, IOWA.

SIGNAL-GOVERNING APPARATUS.

1,412,990.

Specification of Letters Patent. Patented Apr. 18, 1922.

Application filed July 1, 1921. Serial No. 481,986.

To all whom it may concern:

Be it known that I, ALBERTO I. WOODRING, a citizen of the United States of America, and a resident of Waterloo, Blackhawk County, Iowa, have invented certain new and useful Improvements in Signal-Governing Apparatus, of which the following is a specification.

My invention relates to improvements in signal governing apparatus, and the object of my improvement is to supply particularly for use in connection with locomotive whistles, apparatus which may be set by a single manual action of the engineer to act reactively when released upon the whistle valve to provide signal blasts and intervals therebetween of predetermined durations successively.

This object I have accomplished by the means which are hereinafter described and claimed, and which are illustrated in the accompanying drawings, in which Fig. 1 is an elevation of my signal governing apparatus as operatively connected to a whistle, and Fig. 2 is an elevation, in partial section, of the resiliently-controlled detent-carrying winding-drum device.

Similar numerals of reference denote corresponding parts throughout the several views.

Locomotive engineers are required to cause different whistle signals to be made at different places and for different purposes, and particularly are generally required to have a certain signal made at highway-crossings, consisting of two blasts of the whistle of two seconds' duration each, separated by a one second interval, the second blast being followed by a one second interval with following two blasts of the whistle of one second duration each, separated by a one second interval, a total of nine seconds in all. It is, however, often not possible for the engineer to manually control exactly the respective durations of said blasts and their intervals, for his attention is required for other duties.

My improved apparatus for effecting this proper sequence of blasts and their intervals in the required durations thereof may be manually actuated reactively upon a single traction of a pull-cord and its release so that the attention of the engineer is not distracted from a simultaneous duty.

In my device the numeral 1 denotes a

well-known type of locomotive steam-whistle controlled by a valve whose outwardly projecting stem 2 is shifted to open the valve by means of a pivoted lever 3. The numeral 4 denotes a pull-cord connected to a terminal eye in the lever 3 in the usual way but having its other end connected to an eye in a bar 5 which has on its opposite end an orificed angularly extending ear 5'. A short rod 6 is positioned parallel with the bar 5, has a rigid fillet 6' and a diminished terminally threaded part 8 passed through the orifice in the ear 5' with an adjusting nut on its outer end, a coiled compression spring 7 being mounted on said diminished part between the ear 5' and said fillet 6'. A hanger 27 is secured to some elevated support rigidly and has a lateral projection 11 with a terminal abutment 12. On one side face of the projection 11, a lever 13 is pivoted near its curved lower end on a pintle 14, said curved lower end having an offset shoulder 15 crossing it is indicated by the dotted line. The numeral 17 denotes a terminally forked element pivoted to the curved part of the lever 13 on a pintle 16. An anti-friction roller 18 is pivotally mounted between the parts of the element 17, and the opposite end of said element is extended far enough so that the shoulder 15 serves as a stop to limit movement thereof in one direction. In the longer part of the lever 13 is an alined row of bolt holes 9 for adjustably receiving a pintle bolt 10 connecting said lever to the free end of the rod 6.

The numeral 28 denotes a hanger of angular form rigidly bracketed on the opposite face of the hanger 27, and its lower vertical member is medially orificed to receive a rock-shaft 20 on one end of which a winding-drum 19 is fixedly mounted whose circumferential groove receives a pull-cord 25 having a terminal handle 26, the other end of the cord being secured in said groove. One circumferential edge of said drum has a group of circumferentially spaced radial projections 21, 22, 23 and 24, of which the projections 21 and 22 are of the same narrow circumferential width while the other projections 23 and 24 are of the same and a wider circumferential width. All the intervals between said projections are of the same circumferential width. As shown, these relative widths of projections and interspaces are predetermined and in a certain adjustment of the apparatus and while the drum 19

is rocking in one direction reactively, the projections and their intervals will operate to cause blasts of the whistle 1 of a duration and separated by intervals of silence, such as 5 was hereinbefore mentioned.

A spring-barrel 29 is formed rigidly on the lower part of the hanger 27 and has an integrally conjoined dash-pot 30 on its end opposite the winding-drum 19, both the 10 spring-barrel and dash-pot having alined bearing-openings to receive the rock-shaft 20 through certain of their walls, but the end of said shaft extends only far enough into the cavity of the dash-pot to carry a crank- 15 arm 32 whose crank-pin has mounted thereon an anti-friction roller 33 seated in a horizontal groove in a solid piston 34 recipro- 20 cale within the dash-pot which is nearly filled with a cushioning fluid such as oil. A spiral spring 31 is positioned within the barrel 29 around the shaft 20, with its inner end fastened to the shaft, and its outer end fastened to the barrel.

When the pull-cord 25 is pulled down- 25 wardly, it rocks the drum 19 in the direction indicated by the arrow, placing the spring 31 under tension and moving down the piston 34 to cushion the end of the stroke. As the projections 21 to 24 move upwardly, they 30 successively contact with the roller 18 and rock the element 17 without actuating the lever 13. When the pull-cord 25 is released, the spiral spring 31 reacts to rock the drum 19 oppositely, and as the projections 21 to 35 24 successively contact with and rock the element 17 downwardly, the outer end of the element being engaged with the shoulder 15, causes the lever 13 to rock toward said drum imparting a movement to the right to 40 the whistle-lever 3 as each projection trips said element 17 at the predetermined like intervals. The upper edges of the projections 21 to 24 are straight and radial but the lower or opposite edges thereof are slopingly 45 curved so as to prolong their action in connection with the respective different widths of the projections to cause the whistle to give blasts of the required durations as determined by the length of stroke of the lever 50 13 as adjustably connected by the pintle 10 to the rod 6. The spring 7 has a cushioning effect upon these interlinked connections to prevent injurious shocks during actuation and at the end thereof.

55 The abutment 12 on the bracket 11 limits movement to the left of the upper part of the lever 13.

It is obvious that slight changes or modifications in the elements and their arrangement in this apparatus are included in the scope of this invention, and that the apparatus may in principle, be applied to actuate other species of signals as desired.

Having described my invention, what I

claim as new, and desire to secure by Let- 65 ters Patent, is:

1. In combination, a signaling device, and means adapted to be initially set by a single manual impulse and connected thereto to operate it automatically reactively in suc- 70 cessive actuations.

2. In combination, a signaling device, and means adapted to be initially set by a single manual impulse and connected thereto to operate it automatically reactively in a pre- 75 determined succession of actuations and intervals between actuations.

3. In combination, a signaling device, and means connected thereto to operate it in a predetermined succession of variably timed 80 actuations and intervals between actuations.

4. In combination, a signaling device, and means connected thereto to operate it in an adjustably variable succession of actuations separated by adjustably variable intervals. 85

5. In combination, a signaling device, and an operating device therefor connected thereto, said operating device including an elastic element, means for placing said element under tension releasably, and mechanism adapted to be operated by said elastic element after being placed under tension, and then released to actuate said signaling device at successive intervals. 90

6. In combination, a signaling device, and 95 an operating device therefor connected thereto, said operating device including tensionable reaction means adapted to be set initially by a single manual power impulse and then to reactively automatically operate said signaling device in a desired number of successive actuations, with the timing of said actuations and their intervals pre- 100 determined.

7. In combination, a signaling device, and 105 an operating device therefor connected thereto, comprising a rocking element having a plurality of spaced projections, the projections and their interspaces being of predetermined widths, a lever fulcrumed to 110 be engaged and moved by said projections while said element is rocked in one direction only, and linking connections between said lever and said signaling device.

8. In combination, a signaling device, and 115 an operating device therefor connected thereto for manual actuation thereof, comprising a rocking element having circumferential projections separated by spaces, both said projections and spaces being of 120 predetermined widths, a resilient element connected to said rocking element, means for tensioning said resilient element releasably while rocking said rocking element to one position, a pivoted lever operatively connected to said signaling device adjustably, and having thereon a pivoted terminal element engageable yieldably with said pro- 125

jections while the resilient means is being tensioned, and engageable non-yieldingly with said projections while said resilient means is reacting.

- 5 9. In combination, a whistle signal having an operating valve, a pivoted lever operable to actuate said valve, a rocking element having a plurality of circumferential projections of predetermined different widths, 10 separated by spaces of predetermined widths, a pivoted lever having a pivoted terminal and means for limiting movement of said terminal in one direction, said terminal being positioned in the path of rotation of said 15 projections to yieldingly engage them while the rocking element is rocked in one direction and to engage them releasably to rock the second-mentioned lever while the said 20 element is rocked in an opposite direction, adjustable resilient linking-means between said levers, a yieldable resilient body con-

nected between said rocking element and a fixed support, means for manually rocking said rocking element in a direction to place said resilient body under tension releasably, 25 and means for cushioning the rocking element at either limit of its rocking movement.

10. A device of the character described, comprising a resiliently-controlled element manually actuatable releasably in one direction, a movable contact-device, said element having means for successively moving said contact-device at desired intervals and durations only while the element is in reactive movement in another direction after being 35 manually actuated and then released, and operative connections between said contact-device and a movable actuating element of a signaling-device.

Signed at Waterloo, Iowa, this 16th day 40 of June, 1921.

ALBERTO I. WOODRING.
